UNITED STATES PATENT OFFICE.

MINOR W. TAYLOR, OF WATERLOO, IOWA, ASSIGNOR OF ONE-HALF TO
OLIN R. TAYLOR, OF WATERLOO, IOWA.

LUBRICATING DEVICE.

SPECIFICATION forming part of Letters Patent No. 692,558, dated February 4, 1902.

Application filed June 6, 1901. Serial No. 63,370. (No model.)

To all whom it may concern:

Be it known that I, MINOR W. TAYLOR, of Waterloo, in the county of Blackhawk and State of Iowa, have invented certain new and useful Improvements in Lubricating Devices; and I do hereby declare that the following is a full, clear, and exact description thereof, reference being had to the accompanying drawings, and to the letters of reference marked thereon, which form a part of this specification.

This invention relates to improvements in devices for applying lubricating-oil to the bearings of machinery, said device being of that general class comprising a font or receptacle located above the bearings to be lubricated, a plurality of discharge ducts or tubes leading from said receptacle to the several bearings, and a valve mechanism constructed to allow oil to flow from the receptacle to the said ducts or tubes, whereby determinate charges of oil may be passed from the receptacle to the bearings.

My invention is herein shown as applied to oil the bearings of a windmill; but the device may be employed equally well for applying oil to the bearings of machinery of other classes.

The invention consists in the matters herein set forth, and more particularly pointed out in the appended claims.

In the drawings, Figure 1 illustrates the manner of attaching the lubricating device to a windmill and connecting the same with the several bearings thereof, only such parts of the windmill structure being shown as are necessary to illustrate the application of my improvements thereto. Fig. 2 is a rear elevation of the device removed from the windmill. Fig. 3 is a top plan view thereof with the cover of the receptacle removed. Fig. 4 is a top plan view of the tube-supporting plate. Fig. 5 is a front elevation of the device. Fig. 6 is a top plan view of the rotary valve-plate of the valve mechanism. Fig. 7 is a central vertical section of the lower end of the oil font or receptacle, illustrating the valve and oil-distributing mechanism.

As shown in the drawings, A designates 50 the font or receptacle for containing the oil.

Said receptacle is supported on a base-plate B, which is attached in any suitable manner to the machinery to whose bearings oil is adapted to be applied by the device, the receptacle being herein shown as attached to the base-plate by means of bolts b.

Only such parts of the windmill are shown as are necessary to illustrate the application of the device embodying my improvements thereto.

C designates the usual tower-cap, on which is revolvably mounted the rotative head D, which carries the operative mechanism of the mill.

E designates a horizontal bearing-sleeve supported on the upper end of a bracket D', extending upwardly from the head and in which the shaft E' for the motor-wheel is rotatively mounted. E² designates a second horizontal sleeve supported on the bracket D', in which a counter-shaft E³ is mounted. The wheel-shaft is provided with a gear-pinion e, which intermeshes with a gear-wheel e' on the counter-shaft E³. Said gear-wheel e' is provided on one face thereof with a wrist-pin e², which has bearing in an aperture in the upper end of a vertically-reciprocating pitman F, the other end of said pitman being adapted for connection with the upper end of the pump rod or bar. The base-plate B is attached by bolts or the like to a bracket D², projecting upwardly from the bracket D', thereby elevating the font or receptacle above the various bearings, the oil flowing by gravity to the bearings.

The bearings to be oiled herein shown are those for the shaft E', the counter-shaft E³, and the wrist-pin e². For this purpose two oil-cups e³ e³ are provided on the sleeve E, two oil-cups e⁴ e⁴ on the sleeve E², and an oil-cup e⁵ at the upper end of the pitman for the wrist-pin e². Oil tubes or ducts A⁴ A⁵ A⁶ A⁷ A⁸ lead from the receptacle to the various oil-cups, the first two to the cups e³, the second two to the cups e⁴, and the last to the cup e⁵. Said bearings require varying quantities of oil to properly lubricate the same, it being obvious that the bearing for the shaft E' requires more oil to lubricate the same than the bearing for the shaft E³ and that the

wrist-pin requires less oil than the shaft. The valve mechanism by which the supply of oil to the several bearings is controlled is so constructed as to supply varying quantities of oil to the different bearings, as stated. Said valve mechanism is also arranged to supply a uniform amount of oil to each bearing at each usual operation of the valve mechanism, whereby a determinate quantity of oil is assured to each bearing for each operation of the device.

Referring now to the details of the mechanism by which the operations above set forth are performed, said parts are made as follows:

15 The bottom A' of the receptacle A is made flat and is provided with a plurality of annularly-arranged discharge-openings a equal in number to the bearings to be oiled.

I designates a rotative valve-plate, which is 20 located below the bottom of the receptacle A and is rotatively mounted on a short shaft or stud A², depending from said bottom. Said valve-plate is provided with a plurality of annularly-arranged openings i, Figs. 3 and 25 7, which are normally out of line with the openings a in the bottom of the receptacle, as indicated in dotted and full lines in Fig. 3, and are adapted to be brought to register with said discharge-openings when the valve-plate is turned in the proper direction, as 30 shown in Fig. 7. Said valve-plate is provided on its margin with an upwardly-flaring flange I', which fits outside of and overlaps a conical annular part at the bottom of the receptacle, as shown in Fig. 7.

J designates a tube-supporting plate, which is non-rotatively mounted on the stud A² below the valve-plate I and is provided with a vertical annular flange, which fits outside of 40 and overlaps a depending annular flange i' on the valve-plate I. Said valve-plate is provided centrally thereof with upwardly and downwardly projecting annular flanges i² i³, the upper one, i², of which is located in line 45 with the annular recess shown in the bottom A' of the receptacle and the lower one, i³, of which has contact with the inner surface of the tube-supporting plate J and fits within an upwardly-projecting annular flange j' on said 50 plate. The valve-plate and tube-supporting plate are held in position by means of a spiral spring K, surrounding the stud A² and interposed between a boss on the lower side of said plate and a nut A³, which has screw-threaded engagement with the lower end of 55 the stud A². The said tube-supporting plate J is provided with a plurality of openings j², equal in number to and located below the discharge-apertures a of the receptacle A. Said 60 openings j² are surrounded by depending screw-threaded bosses, and the upper ends of the oil tubes or ducts A⁴ to A⁸, inclusive, are connected with said bosses by suitable couplings. A space J' is provided between the tube-supporting plate J and the 65 valve-plate I, which constitutes a distribut-

ing-chamber, into which the oil is fed from the receptacle A when the valve-plate is turned in proper position and from which the oil is directed through the several oil tubes or ducts 70 to the several bearings. The inner face of the tube-supporting plate J is provided between the oil-openings j² therein with a plurality of radial raised ribs j³, which divide the distributing-chamber J' into five compartments, one for each opening j². This construction insures that all of the oil which passes through either of the openings a when one of the openings i of the valve-plate is brought into register therewith will be directed 80 through the proper oil-opening j² in the tube-supporting plate, and thereby insures that a practically uniform quantity of oil will be delivered to each bearing in the successive operations of the device.

The upper face of the valve-plate I may be suitably faced for contact with the lower face of the bottom A' of the receptacle A, whereby said valve-plate may in itself constitute the closure for the discharge-openings a in the 90 bottom of said receptacle; but I prefer, for the sake of economy in manufacturing the device and also to provide for an economical maintenance thereof, to interpose between the said valve-plate and the bottom of said receptacle a yielding gasket M, which is made of a size to fit closely within the upwardly-flaring flange I' of the valve-plate and is provided with an annular series of openings m, adapted to register with the openings i in the valve-plate. With this construction I am enabled to provide a perfect bearing between the contact-faces of the gasket and the bottom of said receptacle without the necessity of accurate machine-work and am enabled also to renew the 105 bearing parts of the valve mechanism at the expense only of providing another gasket, which obviously can be supplied at a much less cost than the valve-plate I. Said gasket may be made of leather or suitably-prepared fiber. 110 The gasket is held from rotation with respect to the valve-plate by means of a lug i⁴, projecting from the flange i² and entering a notch in the inner margin of said gasket. The plate I and gasket obviously together constitute a 115 valve-plate and are in the claims hereinafter so termed.

As before stated, the various bearing parts of the windmill require varying quantities of oil, and to effect this result I make the openings m in the gasket of varying sizes. In the present instance three different sizes of openings are provided, as shown in Fig. 6, the two connected with the tubes leading to the bearings of the shaft E being made the largest, the 120 two connected with the tubes leading to the bearings of the shaft E² somewhat smaller, and the one connected with the tube leading to the wrist-pin bearing being the smallest. The openings a and i in the receptacle-bottom and valve-plate are made of equal diameters. Obviously the same result with respect 125

to the variable supply of oil to the bearings may be secured by making the openings in the bottom of the receptacle of varying sizes.

The valve-plate I is provided with a radially-extending rigid arm I², by which the plate is turned or oscillated. In the normal position of the valve-plate the openings *i* thereof are out of line with the openings *a* in the bottom of the receptacle, as shown in Fig. 10, and the extent of movement of the valve-plate is such that the openings *i* of the valve-plate are brought into register with and pass the discharge-openings *a* in the bottom of the receptacle when the valve-plate is rotated 15 through its complete arc of movement. A suitably-applied spring is connected with the valve-plate in such manner as to return the same when released, and said openings *i* in the return movement of the plate are again 20 brought into register with the openings *a*, thereby bringing said openings *i* and *a* into register twice during each complete operation of the valve-plate. In order to limit or determine the arc of movement of the valve-plate, said plate is provided at one side thereof (on the side adjacent to its actuating-arm, as herein shown) with a short stop-arm I³, which is adapted to engage stop-lugs A² A³ at each end of the travel of the valve-plate, as 25 clearly shown in Fig. 2. As before stated, said tube-supporting plate J is non-rotatively supported on the stud A² and does not therefore turn or rotate with the valve-plate. For this purpose said plate is keyed on the stud, 30 as shown in Fig. 7, the key *j*^a permitting the plate to move endwise of the stud, and therefore to transmit the pressure of the spring K to the valve-plate to hold the same against its seat on the lower face of the receptacle A, 35 while preventing said plate from turning on the stud.

Means are provided which are operable from the foot or base of the tower for actuating the valve mechanism described, said 40 means being constructed as follows:

N designates a bell-crank lever which is pivoted at its angle on a stud *n*, projecting from the base-plate B on the side thereof remote from the oil-receptacle A. Said base-plate is provided with an opening B', through 45 which the valve-plate-actuating arm I² passes, as shown in Fig. 2. One arm of said bell-crank lever is connected by a link O with the outer end of the valve-plate-actuating arm I², 50 said actuating-arm for this purpose being provided with an aperture for engagement with said link. The other arm of said bell-crank lever is fashioned to receive an extension-bar N³, made, preferably, of wood and attached to said arm in any suitable manner. Said extension-bar N³ is connected at its outer end with an operating cord or cable P, 55 Fig. 1, which is adapted to reach to the foot of the tower and is directed downwardly in any suitable manner, so as to avoid contact with the operative parts of the mill.

Q designates a spiral restoring-spring,

which is attached at one end to a lug at the outer end of the arm B² on the base-plate B and at its other end to the outer end of the valve-plate-actuating arm I². With this construction it will be seen that when the outer end of the extension-bar N³ of the bell-crank lever is depressed it acts through the link O and arm A² to rotate the valve-plate I against the action of the spring Q, the movement of said plate being arrested by contact of the stop-arm I³ with one of the stop-lugs A² and the openings *i* and *a* in such movement being brought into register to permit a quantity of oil to drop into each of the compartments of the distributing-chamber J'. When the cable P is released, the spring Q acts to return said valve-plate and to again in such return movement bring said openings *i* into 80 register, whereby a further quantity of oil is fed to said distributing-chamber. The return movement of the plate is arrested by contact of the stop-arm I³ with the other of the stop-lugs A². The extension-bar N³ of the bell-crank lever will be in practice depressed by a quick even movement and when relieved is returned in about the same time, so that it is possible by giving attention to this detail to insure that a practically uniform quantity of oil will be fed to the bearing in the successive operations of the device. By operating the valve mechanism with a slower movement than usual a greater quantity of oil may be fed to the bearing as desired. 95

The device may be provided with any desired number of tubes or ducts for oiling the number of bearings required, it being only necessary to increase the diameter of the receptacle in order to provide space for additional discharge-tubes. Furthermore, should it be desired to use a number of tubes less than the number of discharge-openings in the receptacle and the openings in the valve-plate and tube-supporting plate the device may be readily adapted to the less number of bearings by employing a gasket which is apertured to correspond with the number of bearings to be oiled, the openings in the valve-plate not required in such case being covered and closed by the gasket. 110 115

It is obvious that many changes may be made in the details of construction without departing from the spirit of my invention, 120 and I do not wish to be limited to such details, therefore, except as hereinafter made the subject of specific claims.

I claim as my invention—

1. A lubricating device comprising a single 125 receptacle provided with a bottom wall having a series of discharge-openings, a valve-plate provided with a number of apertures equal to those of the receptacle-bottom, a tube-supporting plate beneath said valve-plate, and a 130 plurality of tubes, one for each aperture of the receptacle-bottom depending from said tube-supporting plate, said valve-plate being movable to bring the apertures thereof into

register with the receptacle-bottom and through said valve-plate apertures to bring the interior of the receptacle into direct communication with the tubes in a manner to permit the oil to flow from said receptacle to and through said tubes.

2. A lubricating device comprising an oil-receptacle, provided in its bottom with a plurality of apertures, a valve-plate provided with an equal number of apertures, the apertures in one of said parts, to wit, the receptacle-bottom or the valve-plate being made of varying sizes, means for moving said valve-plate to bring the apertures thereof into register with the apertures of the receptacle-bottom and tubes depending from the device each receiving the oil which flows through one of the apertures of the valve-plate.

3. A lubricating device comprising an oil-receptacle provided in its bottom with a plurality of apertures, an apertured valve-plate having a yielding facing which engages said apertured bottom of the oil-receptacle, said yielding facing having apertures registering with the apertures of the valve-plate, and some of which are larger than others, tubes depending from the device, each receiving the oil which flows through one of the apertures of the valve-plate, and means for actuating said valve-plate to bring the apertures thereof into register with the apertures of the receptacle-bottom.

4. A lubricating device comprising a receptacle provided in its bottom with an annular series of discharge-openings, a plurality of discharge-ducts equal in number to said discharge-openings, each adapted to receive the oil from one of said discharge-openings and a rotative valve-plate located between the receiving ends of said ducts and said bottom of the receptacle and provided with a plurality of openings corresponding with the openings in said bottom of the receptacle and adapted by rotation of the valve-plate to register with the discharge-openings of said bottom, one of said parts, to wit, the bottom of the receptacle or the valve-plate having openings of varying sizes.

5. A lubricating device comprising a receptacle provided in its bottom with an annular series of discharge-openings, a plurality of discharge-ducts adapted to receive oil from said discharge-openings, a centrally-located stud depending from said bottom of the receptacle, a valve-plate rotatively mounted on said stud between the receiving ends of the ducts and said bottom of the receptacle, said valve-plate being provided with a plurality of openings adapted to register with said discharge-openings of the receptacle, and the openings in one of said parts, to wit, the bottom of the receptacle or the valve-plate, being made of varying sizes.

6. A lubricating device comprising an oil-receptacle provided in its bottom with an annular series of discharge-openings, a distributing-chamber divided into a plurality of

compartments, a plurality of ducts leading from the distributing-chamber, one from each compartment thereof, a centrally-located stud depending from the bottom of said receptacle, a valve-plate rotatively mounted on said stud and provided with a plurality of openings adapted to register with said discharge-openings, the openings in one of said parts, to wit, the bottom of the receptacle or valve-plate, being made of varying sizes.

7. A lubricating device comprising a receptacle provided in its bottom with an annular series of discharge-openings, a rotative valve-plate beneath said bottom of the receptacle provided with a plurality of openings adapted to register with the openings in said bottom of the receptacle, a tube-supporting plate beneath said valve-plate and forming a distributing-chamber, said tube-supporting plate being provided with a plurality of openings located beneath the discharge-openings of the receptacle, means for detachably connecting said valve and tube-supporting plate with the receptacle, and tubes connected with the said openings in the said tube-supporting plate.

8. A lubricating device comprising an oil-receptacle provided in its bottom with an annular series of discharge-openings, a stud depending centrally from said bottom of the receptacle, a valve-plate rotatively mounted on said stud beneath said bottom, and provided with a plurality of openings adapted to register with the discharge-openings of the receptacle, a tube-supporting plate mounted on said stud beneath the valve-plate and provided with a plurality of openings corresponding with the discharge-openings of the receptacle, said valve-plate being provided with annular flanges, one on the upper side overlapping the receptacle, and one on the lower side engaging the tube-supporting plate, a nut on the lower end of said depending stud and a spring interposed between said nut and said tube-supporting plate.

9. A lubricating device comprising a receptacle provided in its bottom with an annular series of discharge-openings, a rotative valve-plate beneath said bottom provided with a series of openings adapted to register with said discharge-openings, an apertured tube-supporting plate located beneath the valve-plate and formed to provide between the same a distributing-chamber, said tube-supporting plate being provided on its upper face with a plurality of radial ribs which divide the chamber into a plurality of compartments and tubes depending from said tube-supporting plate, one communicating with each compartment.

10. A lubricating device comprising a receptacle provided in its bottom with an annular series of discharge-openings, a rotative valve-plate beneath said bottom provided with a series of openings adapted to register with said discharge-openings, an apertured tube-supporting plate located beneath the

- valve-plate and formed to provide between the same a distributing-chamber, said tube-supporting plate being provided on its upper face with a plurality of radial ribs which divide the chamber into a plurality of compartments, tubes depending from said tube-supporting plate, one communicating with each compartment, the openings in the valve-plate and bottom of the receptacle being so formed with respect to each other as to discharge varying quantities of oil from the distributing-chambers therethrough in each operation of the device.
11. A lubricating device comprising a receptacle provided in its bottom with an annular series of discharge-openings, a plurality of discharge-ducts adapted to receive oil from said discharge-openings, a rotative valve-plate located between the receiving ends of said ducts and the discharge-openings of the receptacle, and provided with a plurality of openings adapted to register with said discharge-openings, a gasket interposed between said valve-plate and the bottom of the receptacle and provided with a plurality of openings located in line with the openings in the valve-plate, and interfitting connections between said valve-plate and the gasket preventing relative rotative movement of the gasket and plate.
12. A lubricating device comprising a receptacle provided in its bottom with an annular series of discharge-openings, a plurality of discharge-ducts adapted to receive oil from said discharge-openings, a rotative valve-plate located between the receiving ends of said ducts and said discharge-openings of the receptacle and provided with a plurality of openings adapted to register with said discharge-openings, and a gasket interposed between said valve-plate and the bottom of the receptacle and provided with openings located in line with the openings of the valve-plate, said openings in the gasket being made of varying sizes.
13. A lubricating device comprising an oil receptacle provided in its bottom with a series of discharge-openings, a plurality of discharge-ducts adapted to receive oil from said discharge-openings, and a valve-plate located between the receiving ends of said ducts and said discharge-openings and provided with a plurality of openings which are located normally out of line with the said discharge-openings, and means for moving said valve-

plate to bring the openings therein into register with and past said discharge-openings and a spring for returning said plate to its initial position.

14. A lubricating device comprising a receptacle provided in its bottom with an annular series of discharge-openings, a plurality of discharge-ducts adapted to receive oil from said discharge-openings, a valve-plate located between the receiving ends of said ducts and said discharge-openings of the receptacle and provided with a plurality of openings which are located normally out of line with the discharge-openings, means for actuating said valve-plate to bring the openings therein into register with and past said discharge-openings and to return said valve-plate to its initial position, and interacting stops on the receptacle and valve-plate for arresting said valve-plate at each limit of its movement.

15. A lubricating device comprising a receptacle provided in its bottom with an annular series of discharge-openings, a plurality of discharge-ducts adapted to receive oil from said discharge-openings, a rotative valve-plate located between the receiving ends of said ducts and said discharge-openings of the receptacle, and provided with a plurality of openings adapted to register with said discharge-openings, an actuating-arm on said valve-plate, a lever connected with one end of said arm for rotating the plate in one direction and a restoring-spring connected also with said arm.

16. A lubricating device comprising a receptacle, a plurality of discharge-ducts leading therefrom, a base-plate to which said oil-chamber is attached, a rotative valve-plate controlling the flow of oil from said receptacle to said discharge-ducts, an arm rigid with said valve-plate which passes through an opening in said base-plate, a lever pivoted to said base-plate and connected at one end to said arm, and a restoring-spring attached at one end to said base-plate and at its other end to the arm and acting in opposition to said lever.

In testimony that I claim the foregoing as my invention I affix my signature, in presence of two witnesses, this 3d day of June, A. D. 1901.

MINOR W. TAYLOR.
